[57] CLAIM

The ornamental design for an armband pouch, as shown and described.

DESCRIPTION

FIG. 1 is a perspective view of an armband pouch showing my new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a bottom plan view thereof;

FIG. 7 is a rear elevational view thereof; and

FIG. 8 is a cross-sectional view thereof, taken along the line 8—8 thereof, in the direction of the arrows.

The environmental structure shown in broken lines in FIGS. 1 and 8 is for illustrative purposes only.
